UNITED STATES PATENT OFFICE.

JAMES F. GIBBS, OF WEST LYNN, MASSACHUSETTS.

VENTILATING MECHANISM.

Application filed December 20, 1920. Serial No. 431,832.

To all whom it may concern:

Be it known that I, JAMES F. GIBBS, a citizen of the United States, residing at West Lynn, in the county of Essex and State 5 of Massachusetts, have invented certain new and useful Improvements in Ventilating Mechanisms; and I do hereby declare the following to be a full, clear, and exact description of the invention such as will enable 10 others skilled in the art to which it appertains to make and use the same.

The present invention relates to ventilator mechanisms and more particularly to mechanisms of this character employed for actuating 15 ventilating sections of greenhouses.

The object of the present invention is to provide a ventilator mechanism for greenhouses and similar buildings which is efficient in its operation and does not require 20 space for its installation which might be used for other purposes.

With this object in view one feature of the invention contemplates the provision of a hydraulic ram supported upon the roof 25 of a greenhouse and connected by a suitable system of linkage with the sections of the greenhouse to be opened for ventilating purposes. A further feature of the invention contemplates the provision of a series of 30 hydraulic rams with operating connections between the rams and the several ventilating sections of the greenhouse and a single remote control for causing the actuation of all of the sections simultaneously.

Still further features of the invention consist in certain novel features of construction, combinations and arrangements of parts hereinafter described and claimed, the advantages of which will be obvious to those 40 skilled in the art from the following description.

In the accompanying drawings illustrating the preferred form of the invention Fig. 1 represents a section in elevation of the 45 roof of a greenhouse with the ventilating mechanism supported thereon; Fig. 2 is a detail illustrating a plan view of one of the hydraulic rams and operating connections between the ram and the ventilating section; and Fig. 3 is a partially diagrammatic view 50 illustrating the apparatus for controlling the operation of the several lifting rams.

In the illustrated embodiment of the invention the roof of a greenhouse or similar structure is indicated having a series of 55 longitudinal tubular supports 10 supporting

the inclined glass roof sections 11. Incorporated in the roof may be one or more hinged ventilating sections 13 which are preferably hinged along their upper edge at 60 14 to the ridgepole 15 of the structure. The lifting rams for operating the hinged ventilating sections are supported by the longitudinal supports 10 as indicated in Fig. 1. This supporting mechanism comprises two 65 parallel bars 16 and 17 connected at opposite ends to the supports 10 and having a cylinder 18 connected thereto by brackets 19 and 20. Connected with the cylinder is a frame 22 having parallel guideways 23 which support a sliding crosshead 24 connected with the operating piston 25 by a piston rod 26. The crosshead 24 is connected to an operating arm 28 through a link 29, as shown in Figs. 1 and 2. The arm 28 serves to rock 70 75 the longitudinal shaft 30 which is journaled in a series of supporting brackets 32 secured at intervals to the roof. The rock shaft 30 is connected at intervals with the various ventilating sections through rocker arms 34 80 and rods 35 connecting the outer ends of the arms with the free ends of the sections 13, one arm and a corresponding connecting rod being provided for each of the ventilating sections. It will be observed that with 85 this construction a powerful leverage is exerted for elevating the roof sections into an open position.

Inasmuch as buildings of this sort are largely formed of glass, it is exceedingly important that the building frame be relieved of the strains incident to lifting the various 90 ventilating sections. In order to minimize this strain upon the frame of the building, the present construction has incorporated 95 therein a tie-rod 40 engaging at opposite ends with the rock shaft 30 and with a longitudinal support 10, these tie-rods being disposed at intervals throughout the length of the greenhouse as desired. Each of the tie-rods may be made in two parts indicated at 100 41 and 42 which are held together by a threaded coupling sleeve 43. With this construction it will be obvious that the supporting brackets 32 for the rock shaft are supported and restrained against twisting or bending movements during the operation of the ventilating mechanism by the tie-rods which firmly hold the rock shaft and brackets 105 in a predetermined relation to the longitudinal supporting members 10.

The leverage secured by the actuating

mechanism is such that the hydraulic rams can operate the ventilating sections by the use of water at ordinary pressures of thirty-five to forty pounds per square inch. As will be observed from Fig. 3, each of the rams is connected at the head end with a vertical supply pipe 50, the several supply pipes branching off from the main pipe 52. This main pipe is connected with a source of supply 53, as a city water main, through a valve 54. The supply pipe 52 is also connected with a discharge pipe 55 through a second valve 56. Upon opening the valve 54 with the valve 56 closed all of the ventilating sections are simultaneously raised to the full extent of opening and retained in this position indefinitely, the pressure of water behind the pistons 24 serving to accomplish the necessary lifting of the section. If it is desired to drop the sections slowly, this may be accomplished by opening the valve 56 without closing the valve 54 to allow both the entrance and exit of water from the system. If it is desired to suddenly drop the sections, on the other hand, the valve 56 is opened and the valve 54 wholly or partially closed. It will further be observed that by proper manipulation of one or both of the

valves the ventilating sections may be opened to any desired extent.

While it is preferred to employ the specific construction and arrangement of parts shown and described, it will be understood that this construction and arrangement is not essential except so far as specified in the claim, and may be changed or modified without departing from the broader features of the invention.

The invention having been described, what is claimed is:

A ventilating mechanism for greenhouses and the like comprising a hinged ventilating section, parallel roof supports extending lengthwise of the greenhouse, a hydraulic ram secured to the supports and depending therefrom, a rock shaft having a plurality of operating arms projecting therefrom, means for respectively connecting the arms with the ventilating section and the hydraulic ram, and an adjustable tie rod rigidly connecting the rock shaft with one of the roof supports to cause the stress upon the rock shaft due to the lifting of the ventilating section to be communicated to the support.

JAMES F. GIBBS.
